FIG.1

FIG.2

To all whom it may concern:

Be it known that we, John L. Tedaldi and Jerome A. Gross, citizens of the United States and residents, respectively, of the city of Maplewood, county of St. Louis, State of Missouri, and the city of Clayton, county of St. Louis, State of Missouri, have jointly invented a new, original, and ornamental Design for a Corner Post for Supporting Glass Plates, of which the following is a specification, reference being made to the accompanying drawing, forming a part thereof, in which

Figure 1 is an elevational view of a corner post for supporting glass plates embodying our new design as seen from the inner side of said corner; and

Figure 2 is a side perspective view thereof as seen from below.

We claim:

The ornamental design for a corner post for supporting glass plates, as shown.
